ATTORNEY

UNITED STATES PATENT OFFICE.

FRANK THORNTON, JR., OF MANSFIELD, OHIO, ASSIGNOR TO WESTINGHOUSE ELECTRIC PRODUCTS COMPANY, A CORPORATION OF MICHIGAN.

IMMERSION WATER HEATER.

Application filed September 23, 1921. Serial No. 502,643.

To all whom it may concern:

Be it known that I, FRANK THORNTON, Jr., a citizen of the United States, and a resident of Mansfield, in the county of 5 Richland and State of Ohio, have invented a new and useful Improvement in Immersion Water Heaters, of which the following is a specification.

My invention relates to electrically heated 10 devices and particularly to electrical immersion heaters, and its object is to provide a relatively simple and easily handled electrical immersion heater.

In practising my invention, I provide a 15 tubular heating element which is bent to such shape as to fit into a relatively small fluid container, such as a tumbler, and I provide also a flat elongated switch housing secured to one end of the tubular member, 20 which housing serves to support the heater immediately after it has been withdrawn from the tumbler.

In the single sheet of drawings,

Figure 1 is a view, in side elevation, of an 25 immersion heater embodying my invention as used in a tumbler;

Fig. 2 is a view, in front elevation, of a heater embodying my invention;

Fig. 3 is a view, in side elevation, of a 30 heater embodying my invention located on a suitable supporting surface, and

Fig. 4 is a view, in end elevation, of the heater illustrated in Fig. 3.

An electrical immersion heater 5 comprises, in general, an elongated metal tube 6 within which is placed a resistor element 7 which may be insulated from the inner surface of the tubular member 6 by any suitable means, such as an inner layer of a 40 suitable insulating material 8. The means 8 may be a flexible tube or it may consist of a flexible enamel. If desired, the open space between the helically wound resistor member 7 and the inner surface of the 45 tubular resistor member 8 may be filled with any suitable granular insulating material 9. Such filling will securely hold the resistor member 7 in its proper operative position relatively to the insulating member 8 as 50 well as the adjacent turns of the resistor out of contact with each other.

After the resistor member has been properly placed within the tubular member 6, it may be bent to any suitable or desired 55 form which may be that illustrated in the

figures of the drawing. It is desirable that the two end portions of the tubular member 6 be return-bent, substantially as illustrated in Figs. 1 and 3, for a purpose to be hereinafter set forth.

A suitable control switch 10 comprises two substantially similar housing parts 11 within which is located any suitable or desired tumbler switch mechanism, the operating button 12 of which is illustrated in 60 the drawing. Two bolts 13 and nuts 14 serve to securely clamp the two housing parts 11 against each other and on the outer ends of the return-bent portions of the tubular member 6. A supply-circuit conductor 15 serves to energize the resistor member 7 whenever desired.

When in operation, the immersion heater may be placed in a tumbler 16 in which is 75 a quantity 17 of water which it is desired to heat. After the immersion heater has been energized a sufficient length of time to cause the water to reach the desired temperature, the entire heater may be removed from the position illustrated in Fig. 1 by 80 grasping the switch casing 10 and then placing the heater on a supporting surface, substantially as illustrated in Fig. 3 of the drawing.

It may be noted that the device embodying my invention provides a relatively simple and inexpensive immersion heater which may be handled by the operator without danger of burning the operator when handling the device immediately after removal 90 from the fluid container and that it provides means associated with the heater for supporting the same on any suitable surface in a position which permits of allowing the heater to cool thereon.

Various modifications may be made in the device embodying my invention without departing from the spirit and scope thereof and I desire that only such limitations shall be placed thereon as are imposed by the 100 prior art or are specifically set forth in the appended claims.

I claim as my invention:

1. In an electric fluid heater, the combination with a return-bent tubular heating element, of an elongated switch casing clamped over the ends of said element and effective to support said heating element upon a supporting surface with the casing only in contact therewith.

2. In an electric fluid heater, the combination with a bent tubular heating element, of an elongated switch casing clamped over the ends of said heating element, said casing being adapted to support said heating element upon a supporting surface out of contact therewith.

3. In an electric fluid heater, the combination with an encased heating element adapted to be immersed in a fluid to heat the

same, of a switch casing operatively associated with said heating element for permitting of resting it in an inoperative position on a supporting surface with the switch casing only in engagement therewith.

15

In testimony whereof, I have hereunto subscribed my name this 12th day of Sept., 1921.

FRANK THORNTON, JR.
